UNITED STATES PATENT OFFICE.

ALONZO KIMBALL MARSH, OF NEW YORK, N. Y., ASSIGNEE TO A. KIMBALL COMPANY,
OF NEW YORK, N. Y., A CORPORATION OF NEW YORK.

MARKING-TICKET STRIP.

Application filed August 21, 1922. Serial No. 533,201.

To all whom it may concern:

Be it known that I, ALONZO KIMBALL MARSH, a citizen of the United States, and resident of New York, county of New York, 5 and State of New York, have invented an Improvement in Marking-Ticket Strips, of which the following description, in connection with the accompanying drawings, is a specification, like characters on the drawings representing like parts.

This invention relates to marking tickets such as are secured to garments, fabrics and similar articles for the purpose of indicating the style, size, price or giving other 15 such desirable information, usually in connection with the sale of the article.

The object of the present invention is to provide as an article of manufacture a strip of material presenting a plurality of 20 connected but readily separable marking tickets so constructed that when the tickets are separated from the strip each presents the finished appearance of a separately formed ticket.

25 The object of the invention is further to provide a marking ticket strip comprising a plurality of similar marking tickets so constructed that while the tickets are readily separable from the strip the entire strip may be run through a printing machine or otherwise handled to print thereon the desired indicia for each ticket.

These and other objects and features 30 of the invention will appear more fully 35 from the accompanying description and drawings and will be particularly pointed out in the claims.

In the drawings;

Fig. 1 is a plan view of a portion of a 40 marking ticket strip embodying a preferred form of the invention;

Fig. 2 is a plan view of a single ticket separated from the strip shown in Fig. 1;

Fig. 3 is a sectional view taken on the 45 line 3-3 of Fig. 2;

Fig. 4 is a side elevation showing the ticket illustrated in position upon a piece of fabric.

Fig. 5 is an end view of the ticket strip 50 showing a ticket in flat unbent form and the next secured ticket with the end flaps partially bent away from the plane of the strip on the scored zones.

It is very important that marking tickets, 55 to which this invention relates, shall be

accurately marked. If the indicia marked thereon are erroneous the result is certain to cause dissatisfaction or loss or both, either to the dealer or to the customer. This varies with the nature and value of the 60 articles marked. It is also obviously necessary that similar articles must be marked in exactly the same manner. These and other obvious requirements in the use of marking tickets have led to the devising 65 and adoption of various machines and appliances for stamping or printing upon the marking tickets the desired indicia so as to secure accuracy and uniformity.

One object of the present invention is 70 to present the marking tickets in a continuous strip which may be handled as a unit and thus conveniently presented to the stamping or printing operation. Such a strip may be fed by hand or by automatic 75 means as each impression is made upon each unit of the strip.

The invention also is designed to enable the units or sections of the strip forming the individual marking tickets to be 80 separated readily therefrom and when separated to have the finished appearance of an individually formed ticket. As these marking tickets are mainly used in connection with the retail sale of articles it is desirable 85 that they should have a neat and pleasing appearance. If the edges of the ticket are rough or ragged the effect is undesirable while a marking ticket presenting clean 90 cut edges has a neat and pleasing appearance.

The marking ticket strip of this invention secures these desired results by making use of a folding type of marking ticket and by constructing the strip in the following manner.

The strip may be of any material suitable for marking tickets and is preferably of thin cardboard, heavy paper or what may generally be known as paper board. 100 The width of the strip is equal to the length of the tickets and the length of the strip may be as long as desired. Each strip may contain for example a dozen tickets or may be extended to form a roll of a thousand 105 or more tickets.

A portion of a strip embodying a preferred form of the invention is shown in Fig. 1. In this strip are formed by a suitable scoring operation a plurality of, here- 110

in shown as two, parallel scores 1 and 2 extending longitudinally of the strip and consequently parallel with the edges 3 and 4 of the strip. These scores define the lines 5 upon which the individual tickets are to be folded and consequently the distance of these scores from the edges of the strip will depend upon the desired length of the individual ticket flaps. In order to form the 10 particular preferred type of ticket illustrated these scores are impressed on opposite faces of the strip. For example the score 1 is impressed in the face of the strip opposite to that illustrated in Fig. 1 while 15 the score 2 is impressed in the face illustrated.

The strip is severed on equidistant parallel transverse lines 5, the distance between these lines being determined by the desired width 20 of the individual ticket. These lines of severance 5 extend completely through the strip except at the scored zones 1 and 2. Thus the strip is divided into a plurality of 25 similar marking tickets connected only by the small amounts of material in which the scored zones 1 and 2 are formed.

Since there are a plurality of these connections, two as shown, the tickets are held together in a continuous strip but each is 30 readily separable from the strip simply by rupturing the small scored connections which are weakened by the scoring operation.

The scored connections, it will be noted, occur at the lines of fold of the tickets so 35 that the side and end edges of each ticket are formed by a cutting operation whereby each ticket presents clean cut finished edges giving the ticket practically the same appearance as if it had been individually 40 formed.

The individual tickets of which the strip is composed may be of various styles and construction. The form illustrated is that of a well known type of ticket shown 45 individually in Figs. 2, 3 and 4. Such a ticket comprises two main flaps 6 and 7 of the same size foldable together at the scored zone 1 to receive between them the fabric or article 8 to be marked. A familiar type 50 of wire staple pin fastener 9 is secured to the free edge of the main flap 6 and when the ticket is folded is adapted to pass through the interposed material 8 and a slot 10 formed at the free end of the flap 7 and be 55 bent back against the face thereof. A covering flap 11 is united to the flap 7 by the scored zone 2 and is foldable back over the fastener 9 and extends through a slot 12 in the flap 7 into the space between the main 60 flaps when folded as shown in Fig. 4.

The important feature in the appearance of the ticket is that the portion of the ticket upon which the indicia are displayed shall present the desired neat and pleasing appearance. Consequently the invention in its 65

broader aspects is realized in any form of folding ticket in which the exposed or main flap such for example as the flap 6 is provided with completely severed edges so as to present the desired clean cut finished appearance. The main lines of severance it will be noted extend from one edge of the ticket such as the upper edge illustrated to the scored zone 1 upon which the ticket is folded. From this point to the other edge 70 of the strip the continuations of these lines are weakened, or in other words the tickets on the continuations of these lines are connected by the unsevered weakened portions formed by the scored zones. But in its 75 broader aspect the particular means for weakening the separating lines or the particular location of the narrowed unsevered zones is not important so long as the lines of separation are completely severed in the 80 portion of the ticket forming the main or exposed flap.

It will be seen that a strip embodying this invention may be readily fed by hand or by 85 automatic means through a machine or beneath a stamp so as to imprint the desired indicia successively upon each ticket upon the exposed face of either or both the main flaps. After the strip is printed the individual tickets are readily separated therefrom by rupturing the connecting portions 90 of the material.

Having thus described my invention, what 95 I claim as new and desire to secure by Letters Patent, is:

1. A strip of flexible marking ticket material presenting a plurality of parallel scores extending longitudinally thereof, the said strip being completely severed, excepting at the scored zones, on equidistant 100 parallel transverse lines to form a plurality of similar marking tickets each readily separable from the strip by rupturing the scored connections, each readily foldable on the scored zones, and each presenting clean cut 105 finished edges.

2. A strip of flexible marking ticket material presenting two parallel scores extending longitudinally thereof, one impressed on each face of the strip, the strip being completely severed, excepting at the scored zones, on equidistant parallel transverse lines to form a plurality of similar marking tickets each readily separable from the strip by 110 rupturing the scored connections, each readily foldable on the scored zones, and each presenting clean cut finished edges.

3. A strip of flexible marking ticket material presenting a score extending longitudinally thereof, the said strip being completely severed from one edge to the scored zone and weakened from the scored zone to the other edge on equidistant parallel transverse lines to form a plurality of similar 115 marking tickets each readily separable from 120 125 130

the strip by rupture along the unsevered weakened portion of the transverse lines and each foldable on the scored zone to present a front flap having clean cut finished 5 edges.

4. A strip of flexible marking ticket material presenting a score extending longitudinally thereof, the said strip being completely severed from one edge to the scored 10 zone on equidistant parallel transverse lines and also completely severed, excepting at a

plurality of narrow zones, on the continuations of said transverse lines to the other edge thereby to form a plurality of similar marking tickets each readily separable from the strip by rupturing the narrow unsevered zones and each foldable on the score zone to present a front flap having clean cut finished edges.

In testimony whereof, I have signed my 20 name to this specification.

ALONZO KIMBALL MARSH.
